UNITED STATES PATENT OFFICE.

JOSEPH N. KLEMA, OF AUSTIN, MINNESOTA.

LANTERN.

1,348,810.

Specification of Letters Patent.

Patented Aug. 3, 1920.

Application filed August 30, 1919. Serial No. 320,840.

To all whom it may concern:

Be it known that I, JOSEPH N. KLEMA, a citizen of the United States, residing at Austin, in the county of Mower and State of Minnesota, have invented certain new and useful Improvements in Lanterns, of which the following is a specification, reference being had to the accompanying drawings.

This invention relates to certain improvements in lanterns and has relation more particularly to devices of a hand type, and it is an object of the invention to provide a device of this general character embodying novel and improved means whereby the color screen may be adjusted relative to the burner as the occasions of practice may require, together with novel and improved means whereby the color screen may be maintained in a raised or working position.

20 The invention consists in the details of construction and in the combination and arrangement of the several parts of my improved lantern whereby certain important advantages are attained and the device rendered simpler, less expensive and otherwise more convenient and advantageous for use, as will be hereinafter more fully set forth.

The novel features of my invention will be hereinafter definitely claimed.

30 In order that my invention may be the better understood, I will now proceed to describe the same with reference to the accompanying drawings, wherein:

Figure 1 is a fragmentary vertical sectional view illustrating a lantern constructed in accordance with an embodiment of my invention.

Fig. 2 is a view in bottom plan of my lantern as herein embodied.

40 Fig. 3 is a fragmentary vertical sectional view taken through the base portion of my improved lantern and substantially at right angles to the line of section in Fig. 1.

Fig. 4 is an enlarged fragmentary view 45 partly in section and partly in elevation illustrating the spring clips coacting with the operating lever for holding the same in folded position.

Fig. 5 is a fragmentary view in side elevation illustrating a connection between an operating lever and the depending arm of a holder.

Fig. 6 is a fragmentary view in side elevation of the structure shown in Fig. 5.

55 Fig. 7 is a longitudinal sectional view

taken through the structure as particularly illustrated in Figs. 5 and 6.

Fig. 8 is a fragmentary view partly in section and partly in elevation illustrating the means for maintaining a holder in raised 60 position.

Fig. 9 is a view in perspective of one of the screen holders as herein embodied.

As disclosed in the accompanying drawings, C denotes a casing of a conventional 65 type generally employed in connection with a hand lantern of a railroad type and which is mounted at substantially the center of the cocavo-convex base 1 having its concave face downwardly directed.

Supported by the base 1 and arranged substantially central of the casing C is a burner B of a conventional type. Coacting with the casing C is a well known type of globe D.

The base 1 inwardly of the casing C is provided with a pair of substantially radially aligned openings 2, each substantially defined by a sleeve 3 preferably angular in cross section and which sleeve is of a length 70 to terminate inwardly of the peripheral portion of the base 1. Each of the sleeves 3 is provided in a face thereof and adjacent the lower end thereof with an opening 4 for a purpose which will hereinafter be more 75 particularly referred to.

In the present embodiment of my invention two transparent screens S of different colors are adapted for coaction with the burner B so that when either of said screens 80 is in an elevated position the rays of light emitted from the lantern will be in accordance with the color of the screen. Each of the screens is supported by a holder H and said holder H comprises a short arm 5 85 which, when the holder H is in lowered position extends through a sleeve 3 and said arm 5 is of a length to terminate immediately adjacent the lower end of the sleeve 3 when said holder is in its lowered position. 90 The upper end portion of the arm 5 is provided with a pair of oppositely directed arcuate arms 6. Each of the arms 6 is relatively short and is provided at its outer extremity with an upwardly facing hook member 7 in which is adapted to seat the lower portion of a color screen S. The color screen S is tubular in form and substantially concentric to the burner B and surrounds said burner B when in its lowered position.

100 Fig. 8 is a fragmentary view in side elevation illustrating a connection between an operating lever and the depending arm of a holder.

105 Fig. 9 is a fragmentary view in side elevation of the structure shown in Fig. 8.

110 Fig. 10 is a longitudinal sectional view

When raised, the screen S surrounds the flame of the burner so that the light rays emitted will be in accordance with the color of the screen.

5 Secured to the upper portion of the arm 5 is an upwardly directed resilient strip 7 and provided at its upper end with an inwardly directed hook or lug 8 adapted to engage over the top of the coacting screen S 10 whereby said screen S is effectively held by the holder H for movement therewith in either direction. At this time it is to be stated that the screens S are of different diameters so that one of said screens may 15 telescope within the other and so that each of said screens may be raised or lowered independently of the other.

The lower end portion of the arm 5 is provided with a tenon or lip 9 extending with- 20 in a kerf 10 in an end portion of an elongated operating lever or arm 11 and pivotally held as at a within said kerf. A side 25 of the arm 11 has secured thereto a spring 12 having one end portion closing a side 30 of the kerf 10 and coacting with the tenon or lip 9 so that when the arms 5 and 11 are in longitudinal alinement, the same are held against relative movement so that when the holder H and the screen S engaged there- 35 with are in raised position the screen is held against lateral movement which would otherwise impair the efficiency thereof.

When the holder H is in its lowered position the arm 11 has swinging movement 40 toward the base 1 in a direction away from the spring 12. The arm 11, when its coacting holder H is in its lowered position, is adapted to be substantially housed within the base 1 and in order to maintain the same 45 in such position the outer or free end portion thereof is engaged between the spring clips 14 depending from the base 1.

Extending outwardly from the outer or 45 free end portion of the arm 11 is a pair of transversely spaced ears 15 with which are pivotally engaged the ears 16 carried by an elongated arm 17. The arm 17 is disposed longitudinally of the arm or lever 11 and its inner end portion is constantly urged 50 toward the arm or lever 11 through the medium of the spring 18. The inner end portion of the arm 17 is provided with an inwardly directed and suitably curved extension 19 so that as the arm or lever 11 is 55 forced upwardly through the sleeve 3 to raise a holder H the inner end portion of the arm 17 will readily ride over the lower end portion of the sleeve 3 and engage within the opening 4 so that the holder H will 60 be held in its raised position. When it is desired to lower the holder H it is only necessary to depress the outer end portion of the arm 17 sufficiently to retract the inner

end portion of said arm or more particularly the extension 19 thereof from within the 65 opening 4.

It is to be understood that this present application is partly in continuation of my former application Serial No. 197,663, filed October 20, 1917. 70

From the foregoing description, it is thought to be obvious that a lantern constructed in accordance with my invention is particularly well adapted for use by reason of the convenience and facility with which 75 it may be assembled and operated and it will also be obvious that my invention is susceptible of some change and modification without departing from the principles and spirit thereof and for this reason I do not 80 wish to be understood as limiting myself to the precise arrangement and formation of the several parts herein shown in carrying out my invention in practice except as herein- 85 after claimed.

I claim:

1. A lantern comprising a base provided with an opening, a sleeve depending from the base and substantially defining the opening, a burner supported by the base, a transparent member surrounding the burner, an arm depending from the member and extending within the sleeve when the member is in its lowermost position, said sleeve being provided with an opening in a wall 95 thereof, an operating lever pivotally engaged with the lower end portion of the arm, an arm carried by the lever, means for constantly urging the inner end portion of the arm toward the lever, said inner end portion being provided with an inwardly curved extension, said inwardly curved extension engaging within the opening in the wall of the sleeve when the lever is moved upwardly through the sleeve to raise the 100 transparent member.

2. A lantern comprising a base provided with an opening, a sleeve depending from the base and substantially defining the opening, a burner supported by the base, a transparent member surrounding the burner, an arm depending from the member and extending within the sleeve when the member is in its lowermost position, an operating lever pivotally engaged with the lower end 110 portion of the arm, means carried by the arm and engageable with the sleeve for holding the transparent member in an elevated position, said lever longitudinally alining with the arm when the transparent member 115 is raised, and means for normally maintaining said arm and lever against displacement when alined.

In testimony whereof I hereunto affix my signature.

JOSEPH N. KLEMA.
